UNITED STATES PATENT OFFICE.

FRANK D. HOBBS AND CLARENCE HOBBS, OF LOS ANGELES, CALIFORNIA.

ROLLER SCREEN.

Application filed January 11, 1926. Serial No. 80,676.

Our invention is a roller screen for windows and the general object thereof is to provide a screen of this type which will be simple in construction, easy to assemble and 5 install, economical, and efficient in operation.

Other objects and advantages will appear hereinafter.

The invention is illustrated in the annexed drawing which forms a part of this specification, and in which—

Figure 1 is a transverse vertical section of a window and a roller screen embodying our invention, taken on line 1—1 of Figure 2.

Figure 2 is a front vertical section taken 15 on line 2—2 of Figure 1.

Figure 3 is a fragmentary horizontal section taken on line 3—3 of Figure 1.

Figure 4 is a modified fragmentary transverse-vertical section with the screen roll 20 removed.

Corresponding reference characters designate the same parts in all the views.

In the drawing 1 indicates a window frame including side stops 2, upper stop 3, 25 side jamb members 4, and a jamb header 5.

In the under side of the jamb header 5 we cut a longitudinal groove 6 forwardly of the upper sash 7. In the upper part of the frame 1 and within the groove 6 we place a 30 roller mounting 8 and a screen roller 9 which is mounted in said mounting. The mounting 8 may be formed of a single piece of sheet metal and comprises a bottom horizontal wall 10, end walls 11 bent upwardly from the ends of said bottom wall and back 35 downwardly upon themselves, a rear wall 12 bent upwardly from the rear edge of said bottom wall to about half the height of said end walls, a horizontal flange 13 bent rearwardly from the upper edge of said rear wall, and a flange 14 bent upwardly from the forward edge of said bottom wall. The mounting 8 is placed with its end walls 10 against the inside of the side jamb members 4, with its rear wall 12 immediately in front 40 of the upper sash 7 and with its flanges 13 against the under side of the jamb header 5 above the sash. The outside members 15 of the end walls 11 extend below the bottom wall 10 and screws 16 are driven through the lower ends of said members into the side jamb members 4 whereby the mounting 8 is detachably mounted in the upper 50 part of the window frame and within the groove 6.

The inner members of the end walls 10

are formed with offsets 17 provided with square holes 18 to receive the square ends 19 of the shaft 20 of screen roller 9 whereby said shaft is held in the mounting 8 against turning. On the shaft 20 at the ends thereof are journaled a pair of cylindrical wooden blocks 21 over which is fitted and to which is secured a cylindrical roller tube 22, the ends of which tube extending to the end walls 10 and over the offsets 17. A spring 23 is coiled around the shaft 20 and secured at one end to the shaft at 24 and at its other end in one of the blocks 21 at 25, which spring normally winds a screen 26 on the 70 tube 22 of the roller, the upper end of the screen being secured to the tube at 27.

The lower end of the screen 26 is secured in a clamp 30 which consists of an outer clamp member 31 and inner clamp member 75 32. The outer member is offset inwardly at 33, while the inner member is bent inwardly upon itself at its upper edge at 34 and at its lower edge at 35 which latter portion fits over the outside of the lower portion of member 31 below the offset 33. The lower end of the screen is held between the members 31 and 32 and is bent inwardly by the offset 33 under the upper bent portion 34 of the inner member 32 whereby the screen is held 80 securely within the clamp so that it cannot pull upwardly out of the same. The clamp members 31 and 32 are secured together by wood screws 36 which extend outwardly through the members 32 and 31 into a wooden strip 37, thus securing the strip and clamp together. The ends of the clamp 30 and the side edges of the screen 26 extend into 85 grooves 39 in the side stops 2.

In the strip 37 are pivoted vertical spring 95 catches 40 which extend through the strip and through catch casings 41 fitted in the strip, the catches being pivoted by pins 42 secured in said casings. Springs 43 are provided in said casings which urge the catches 100 40 into engaging position. The window sill 44 is provided with recesses 45 and slotted catch plates 46 provided with slots 47 are secured to the sill 44 by screws 48 with the slots 47 over the recesses 45.

When the screen 26 is drawn down off the roller 9 the catches 40 extend through the catch plate slots 47 into the sill recesses 45 and engage the under side of the plates 46 whereby the screen is held down against the 110 tension of the roller spring 23 over the front of the window. Upon releasing the catches

40 from the plates 46 the spring 23 winds the screen upon the roller.

The modified form of the circular flange 13^a disclosed in Figure 4 is integral with the 5 rear straight wall 12 and is curved therefrom around the adjacent face of the groove 6 to form a reinforcing housing 50 to protect the screen roller 9 from damage and moisture, should the jamb header 5 become broken or 10 be dispensed with in the window frame, the extended end 13^b of the flange 13^a being formed to be secured in the adjacent framing between the header 5 and the stop 3.

We claim—

- 15 1. In a screen roller, a mounting comprising a bottom wall, end walls, a rear wall, and a rear flange extending from the upper edge of said rear wall, the mounting being fitted in a groove cut in the under side of 20 the jamb header of a window frame with said rear wall resting in front of the window sash, said rear flange resting against the under side of the jamb head over said sash, and said end walls resting against the 25 side jamb members of the frame, means for securing the end walls of the mounting to the side jamb members, a roller mounted in said mounting, a screen secured and wound on said roller to be drawn down in front 30 of the window frame, and means for holding the screen drawn down.
2. In a roller screen, a mounting comprising a bottom wall, a rear wall upstanding from the rear edge of said bottom wall, a 35 rear flange extending from the upper edge of said rear wall, and end walls, said end walls being bent upwardly from the ends of said bottom wall and then downwardly upon themselves and the upwardly bent portions 40 being formed with offsets provided with flat-sided openings, the mounting being fitted in

a groove cut in the under side of the window jamb header with the rear wall of the mounting resting in front of the window sash, said rear flange resting against the 45 under side of the jamb head over said sash, and said end walls resting against the side jamb members of the window frame, means for securing the end walls of the mounting to the side jamb members, a roller constructed 50 with a shaft with flat-sided ends adapted to fit in said flat-sided openings in said offsets, a screen secured and wound on said roller to be drawn down in front of the window frame, and means for holding the screen 55 drawn down.

3. In a roller screen, a mounting comprising a bottom wall, a rear wall upstanding from the rear edge of said bottom wall, a rear flange extending from the upper edge 60 of said rear wall, and end walls, said end walls being bent upwardly from the ends of said bottom wall and then downwardly upon themselves below said bottom wall, the lower ends of the downwardly bent portions of 65 said end walls being provided with screw holes to receive screws for securing the end walls to the side jamb members with the mounting fitting in a groove cut in the under side of the window jamb header, with 70 said rear wall resting in front of the window sash and with said rear flange resting against the under side of the jamb head over said sash, a roller mounted in said mounting, a screen secured and wound on said roller to 75 be drawn down in front of the window frame, and means for holding the screen drawn down.

In testimony whereof we affix our signatures.

FRANK D. HOBBS.
CLARENCE HOBBS.
